UNITED STATES PATENT OFFICE.

EUGENE J. RAY, OF BEVERLY, MASSACHUSETTS, ASSIGNOR TO UNITED SHOE MACHINERY COMPANY, OF PATERSON, NEW JERSEY, A CORPORATION OF NEW JERSEY.

BUTTONHOLE-SEWING MACHINE.

1,197,953.

Specification of Letters Patent. Patented Sept. 12, 1916.

Application filed December 13, 1915. Serial No. 66,531.

To all whom it may concern:

Be it known that I, EUGENE J. RAY, a citizen of the United States, residing at Beverly, in the county of Essex and State 5 of Massachusetts, have invented certain new and useful Improvements in Buttonhole-Sewing Machines; and I do hereby declare the following to be a full, clear, and exact description of the invention, such as will 10 enable others skilled in the art to which it appertains to make and use the same.

The invention relates to buttonhole sewing machines in which a work holding clamp and sewing mechanism are relatively 15 movable to form overseam stitches along the sides and about the ends of a buttonhole.

The object of the invention is to improve and simplify the clamp closing and clamp opening mechanism of machines of this 20 type, and to that end the invention comprises the features of construction and combinations of parts hereinafter described and set forth in the claims, the advantages of 25 which will be apparent to those skilled in the art from the detailed description of the preferred form of the invention.

The invention will be readily understood from an inspection of the accompanying drawings and the following detailed description of the mechanism illustrated 30 therein.

In the drawings, Figure 1 is a vertical sectional elevation showing so much of a buttonhole sewing machine as is necessary 35 to illustrate the application of the present improvements thereto; Fig. 2 is a plan view showing the work holding clamps and the upper face of the main cam carrying gear disk; Fig. 3 is a detail view of the work 40 holding clamps showing the clamps in closed position; Fig. 4 is a similar view showing the parts as the clamps are opening; and Fig. 5 is a detail showing the cam for closing the clamps.

The invention is shown as embodied in a buttonhole sewing machine having the general construction and mode of operation of the machine shown and described in Patent No. 1,063,880, June 3, 1913. In this machine the stitch forming mechanism comprises an upper needle 2, an under needle 4, and a looper 6. The upper needle is eccentrically mounted in a reciprocating needle bar 8 carried in a rotary head 10. The under needle and looper are mounted

in a rotary turret 12. The turret and head are rotated through a single revolution during the sewing of a buttonhole from a gear 14 which makes a single revolution during the sewing, and is connected with the turret 60 and head through mechanism fully described in the patent above referred to. The buttonhole slit is cut prior to the sewing by a cutter 16 carried by a cutter lever 18 which is operated by a cam 20 secured to 65 the upper face of the cam carrying gear disk 22. The work holder comprises upper and lower clamping members mounted upon a carrier 24 which is moved lengthwise of the buttonhole to move the work between 70 the clamping and cutting and the sewing positions, and to feed the work during the sewing by a cam groove formed in the under face of the cam disk 22 and engaging a roll carried by a stud 26 on the carrier. The 75 stud passes through a fulcrum block 28 arranged to slide in a guideway formed in the base plate of the machine, and the carrier is moved laterally during the sewing about the eye and end of the buttonhole by 80 a cam formed in the upper face of the gear 14 and engaging one end of a lever 30, the other end of which is pivotally connected to a block 32 mounted in a slot in the rear end of the carrier. 85

In the construction shown, the work clamping members comprise the work supporting plates 34 provided with the lower clamping blocks 36 and upper clamping jaws 38 pivoted to the ends of the clamp 90 carrying arms 40. The clamp carrying arms are pivotally supported in blocks 42 adjustably secured in the plates 34, and are forced upward by springs 44. The means for closing the clamp comprises a rock shaft 95 46 mounted in bearings 48 on the carrier 24, and provided with flat spring arms 50 which are mounted to bear upon the clamp arms 40 near their forward ends. A torsional spring 52, having one end connected 100 with one of the bearings 48 and the other end connected with the rock shaft, tends to raise the arms 50 and thus open the clamp. The rock shaft is provided with a rearwardly projecting arm 54 which is arranged 105 to be engaged by a cam 56 on the cam carrying disk 22 when the work holder is in retracted or buttonhole cutting position. The rock shaft is also provided with a vertically projecting arm 58, the upper end of which 110

is arranged to be engaged by a latching shoulder 60 on the latch lever 62 when the clamp is closed. The latch thus acts to hold the clamp in closed position, as indicated in Fig. 3, after the clamp has been closed by the cam 56, and while the arm 54 is free from the cam 56 during the forward and return travel of the clamp carrier. The latch lever is operated to release the rock shaft and thus effect the opening of the clamp by a dog 64 pivoted to the machine frame, and arranged to be engaged by an upwardly extending arm 66 on the latch lever. The dog 64 is so pivoted that during the forward travel of the clamp the arm 66 of the latch lever will ride idly under the dog, swinging it up about its pivot. As soon as the arm on the latch lever has passed, the dog will swing down into normal position, and during the last part of the return movement of the work clamp the dog will depress the arm 66 of the latch, thus raising the latch to release the rock shaft 46 and effect the opening of the clamp.

25. In order to avoid the sudden and violent movement of the rock shaft under the influence of the spring arms 50 when the latch is released, means is provided for controlling the clamp opening movement of the rock shaft so that it moves gradually into clamp opening position. As shown, this means comprises a fixed arm 68 arranged to engage a surface 70 on the upper side of the latch lever as the latch is lifted by the dog 64, and a controlling surface 72 formed on the latch lever back of the latching shoulder 60 and arranged to engage the end of the arm 58 when it is disengaged from the latch shoulder. The two controlling surfaces 70 and 72 are so shaped and located with relation to the arms 68 and 58 that during final backward travel of the work clamp after the latch shoulder 60 has been disengaged from the arm 58, the latch lever gradually rises, so that the clamp opening movement of the rock shaft is controlled by the engagement of the surface 72 with the arm 58, and a sudden and violent movement of the rock shaft is prevented.

50. While it is preferred to employ the specific construction and arrangement of parts shown and described, in embodying the invention in the machine of the patent above referred to, it will be understood that this construction and arrangement is not essential to the broader features of the invention, and may be varied or modified as found desirable or best suited to the construction of the machine in which it is to be embodied.

Having explained the nature and object of the invention, and specifically described one form of mechanism in which it may be embodied, what is claimed is:—

65. 1. A buttonhole sewing machine, having,

in combination, stitch forming mechanism, a clamp carrier provided with work clamping members, a controlling rock shaft on the carrier provided with an arm, a feed cam disk, and a cam on the feed cam disk for directly engaging the arm to effect the closing of the clamping members. 70

2. A buttonhole sewing machine, having, in combination, stitch forming mechanism, a clamp carrier, a feed cam disk for relatively feeding the clamp carrier and stitch forming mechanism to sew about a button-hole, work clamping members on the carrier, a rock shaft on the carrier connected to close the clamping members, an arm on the rock shaft, a cam on the feed cam disk for directly engaging the arm to effect the closing of the clamping members; and means for retaining the shaft in clamp closing position during the feed. 75

3. A buttonhole sewing machine, having, in combination, stitch forming mechanism, a clamp carrier, a feed cam disk for relatively feeding the clamp carrier and stitch forming mechanism to sew about a button-hole, work clamping members on the carrier, a clamp closing cam on the feed cam disk, a rock shaft on the carrier connected to close the clamping members, an arm on the rock shaft moved out of and into the path of the clamp closing cam by the relative movement of the clamp carrier and stitch forming mechanism, and means for retaining the shaft in clamp closing position while the arm is out of the cam path and for releasing the shaft to effect the opening of the clamping members. 80 90 95

4. A buttonhole sewing machine, having, in combination, stitch forming mechanism, a clamp carrier, a cam disk provided with a cam for relatively feeding the stitch forming mechanism and carrier and a clamp closing cam, clamp carrying arms pivotally mounted on the carrier, a rock shaft provided with arms acting on the clamp carrying arms, and a third arm on the rock shaft arranged to directly engage the clamp closing cam on the feed cam disk when the clamp carrier is in work receiving position. 105 110

5. A buttonhole sewing machine, having, in combination, stitch forming mechanism, a clamp carrier provided with work clamping members, a rock shaft provided with spring arms for closing the clamping members; means for retaining the rock shaft in clamp closing position, and means for releasing the rock shaft and controlling its clamp opening movement. 115 120

6. A buttonhole sewing machine, having, in combination, stitch forming mechanism, a clamp carrier provided with work clamping members, a rock shaft provided with spring arms for closing the clamping members, means for retaining the rock shaft in clamp closing position, and means for re- 125 130

leasing and for securing a gradual clamp opening movement of the rock shaft.

7. A buttonhole sewing machine, having, in combination, stitch forming mechanism, 5 a clamp carrier provided with work clamping members, a rock shaft provided with spring arms for closing the clamping members, means for rocking the shaft to effect

the closing of the clamping members, an arm on the rock shaft, a latch lever for engaging the arm to retain the rock shaft in clamp closing position, and means for actuating the latch lever to permit the gradual clamp opening movement of the rock shaft. 10
